MERCHANDISING DISPLAY STAND FOR WRITING INSTRUMENTS AND THE LIKE

Thaddeus I. Kingsford, Chamblee, and Frank Van Haltren, Jr., Atlanta, Ga., assignors to Scripto, Inc., a corporation of Georgia

Filed Jan. 3, 1966, Ser. No. 419

Term of patent 14 years

(Cl. D80—9)

FIG. 4

FIG. 1 is a perspective view of the merchandising display stand for writing instruments and the like embodying our new design;

FIG. 2 is a front elevational view;

FIG. 3 is a side elevational view; and

FIG. 4 is a top plan view thereof.

We claim:

The ornamental design for a merchandising display stand for writing instruments and the like, as shown.
